Richard Oliver,

ATTORNEY

UNITED STATES PATENT OFFICE.

MILEDEN S. MONDAY, OF CANEY, OKLAHOMA.

RAIL-JOINT.

1,272,498.

Specification of Letters Patent. Patented July 16, 1918.

Application filed April 22, 1918. Serial No. 230,116.

To all whom it may concern:

Be it known that I, MILEDEN S. MONDAY, a citizen of the United States, residing at Caney, in the county of Atoka and State of Oklahoma, have invented certain new and useful Improvements in Rail-Joints, of which the following is a specification.

This invention relates to railway rail joints, and it relates more particularly to an improved form of rail chair or saddle for supporting the meeting ends of railway rails between the cross ties.

One of the objects of the invention is to provide a device of this character which is easily applied after the rails have been secured in place upon the ties.

Another object of the invention is to provide a device of this character which is so simple of construction as to be comparatively inexpensive.

Another object is to provide a device of this character which is thoroughly practical, effective and efficient.

Other objects and advantages may become apparent to persons who read the following details of description in connection with the accompanying drawings in which—

Figure 1 is a top plan view illustrating the meeting ends of two rails with my improved saddle or truss support associated therewith.

Fig. 2 is a side elevation of the construction shown in Fig. 1.

Fig. 3 is a cross section of my truss support taken on a plane between the meeting ends of the rails and

Fig. 4 is a perspective view of one of the improved fish plates which is used in connection with my improved truss support.

Referring to these drawings in which similar reference characters correspond with similar parts throughout the several views, the rails A are of the ordinary counterpart construction, and are not described in detail. My improved truss support or rail end support comprises a plate of heavy sheet metal which is substantially U-shaped, so as to form a depending rail seat 5, vertical supports 6 therefor, and horizontally and oppositely extending end portions 7. The rail seat 5 is of sufficient width to insure a substantial foundation on which the meeting rail ends rest, while being sufficiently narrow to extend between two adjacent cross ties. The end portions 7 rest respectively upon two truss bars 8 each of these

truss bars being substantially square in cross section at its middle portion, that is, at the portion upon which the corresponding element 7 is seated; while the end portions of each truss bar are substantially L-shaped in cross section or each comprises a horizontally extending flange 9 and a vertically extending flange 10. The horizontally extending flanges are each provided with one or more apertures 11 for receiving railway spikes whereby the truss bars are secured to the cross ties, while the vertically extending flanges are provided with apertures 12 for receiving bolts to secure the improved fish plate in position. Any proper fastening means may be employed for securing the elements 7 to the truss bars 8, bolts 13 being shown for this purpose in Fig. 3.

Each one of the truss bars is provided with an angular lug 14 at each end, these lugs being adapted to engage with the edges of the tie so as to limit the relative movement of the truss support and rails longitudinally of the latter.

My improved fish plate illustrated in Fig. 4 is preferably formed of a single blank of heavy sheet metal; the blank being substantially rectangular and provided with a substantially rectangular notch 15 in one of its longitudinal sides. This fish plate which is designated by the numeral 16, is also provided with apertures 17 which register with corresponding apertures 12 of the truss bars; apertures 18 being provided in each fish plate for receiving bolts which extend therethrough and through the webs of the rails for securing the fish plates to the rails in the ordinary manner. Each fish plate is preferably provided with horizontally extending flanges 19, each of said flanges extending from the notch 15 to the end of the fish plate. These flanges 19 normally rest upon the tops of the respective truss bars 8. That is, they rest, respectively on the flanges 10 of the truss bars. It will be seen, therefore, that the elements 7 fit within the corresponding notches 15 and coöperate therewith for preventing relative movement of the fish plates and truss bars longitudinally of the latter. Moreover, it will be seen that the meeting ends of the rails are effectively supported not only by the plate 5, but also by the coöperation of the fish plates and the truss bars; also, that these elements mutually coöperate to prevent the separating of the rails at their meeting ends. Therefore, it

will be seen that I have provided a device of this character which supplies a great need in railroad construction, and which will obviate such accidents that so often occur because of the failing of the railway track.

Although I have described this embodiment of my invention in minute detail, it is to be understood that my invention is not limited to these exact details of construction and arrangement of parts; but I am entitled to make such changes that do not constitute a departure from the inventive idea disclosed in the foregoing description, drawings and appended claims.

What I claim as my invention is:

1. The combination with two cross ties and with two meeting ends of railway rails, supported by said ties, of a pair of truss bars seated on two adjacent ties and disposed at opposite sides of said meeting ends of the rails, and a substantially U-shaped plate having its middle portion under said meeting ends and having its end portions seated on and secured to said truss bars, and having elements which connect said end portions with said intermediate portion seated substantially against the longitudinal edges of the bases of the rails, whereby the rail

ends are supported against downward and lateral movement.

2. The combination with two railway ties and with the meeting ends of two railway rails, of a pair of truss bars each having its ends secured respectively to said ties, said truss bars being disposed at opposite sides of the rail ends, and being of a height considerably greater than the height of the rail base flanges, a supporting plate having its end portions seated respectively on said truss bars and having its intermediate portion depending from said end portions and disposed in position for supporting said meetings ends of the rails and a pair of fish plates each provided with means for securing it to the rail web and with means for securing it to the adjacent one of said truss bars, each of said fish plates being provided with a notch into which said end portions of said supporting plate fit so as to prevent relative movement of the fish plates and truss bars longitudinally of the latter.

In testimony whereof I affix my signature in presence of two witnesses.

MILEDEN S. MONDAY.
